U.S. Appl. No. 29/381,822, filed Dec. 23, 2010, Marc Zemel.

* cited by examiner

Primary Examiner — Austin Murphy(74) Attorney, Agent, or Firm — Carter, DeLuca, Farrell & Schmidt LLP(57) CLAIM

The ornamental design for a grill brush, as shown and described.

DESCRIPTION

FIG. 1 is a front elevational view of a grill brush in accordance with the present design, the rear elevational view being a mirror image thereof;

FIG. 2 is a side elevational view thereof, the opposite side being a mirror image thereof;

FIG. 3 is a top plan view thereof; and,

FIG. 4 is a bottom plan view thereof.

The broken lines shown are included for the purpose of illustrating a portion of the grill brush that forms no part of the claimed design.
